HEAT DISSIPATING FIXTURE

Vivian Luther Westberg, Chicago, Ill., assignor
to Benjamin Electric Mfg. Company, Des
Plaines, Ill., a corporation of Illinois

Application March 3, 1933, Serial No. 659,518

7 Claims. (Cl. 240—47)

This invention relates to heat dissipating electric fixtures and heat conducting means therefor, and more particularly to electric fixtures where in a heat conducting and dissipating means is provided between a reflector and a casing whereby the heat from a light source may be readily conducted from the reflector to the casing and dissipated therefrom.

In many electric fixtures and particularly in enclosed fixtures, such as floodlights, vapor-proof and explosion-proof fixtures, the heat from the electric bulb used therein creates a very high temperature within the casing which is often sufficient to cause a tarnishing of the reflector or entirely destroying the finish thereon. This is particularly true with glass reflectors which usually have a coating of silver on the outside to provide a reflecting surface. Also the electric bulb will sometimes become distorted or even explode due to the excessive heat.

It is, therefore, an object of the present invention to provide an electric fixture in which the heat from the reflector is rapidly and uniformly conducted to the casing and dissipated therefrom to the outside atmosphere, and wherein by rapidly conducting the heat from the reflector to the casing the temperature around the lamp is reduced and the life of the bulb, as well as the reflector and entire fixture, is considerably increased.

A further desirable feature of the present invention is the provision of a fixture in which is incorporated a structure which not only conducts heat rapidly to the outer casing where it may be rapidly dissipated but also allows and assists in promoting uninterrupted air circulation within the fixture and over large surfaces of high heat-conducting characteristics.

It is a further object to provide a heat-dissipating device for electric fixtures which may be easily applied between a reflector and a casing and which will readily adapt itself to the shape of the reflector and casing and provide a sufficient contact area to rapidly conduct the heat outwardly, and which will not interfere with air circulation in any fixture to which it may be applied.

The present invention also provides a heat-conducting device for electric fixtures which is of suitable material and is so constructed and applied as to combine the characteristics of high heat conductivity and sufficient resilience to maintain the device snugly in position.

It is also an object to provide a heat-dissipating device which is cheap to manufacture, easy to assemble in a reflector, and which readily

adapts itself to various shapes of reflectors and casings within reasonable limits.

Other objects and advantages will be apparent from the specification and the appended claims.

In the drawings:

Fig. 1 is a side elevation partially in section of an electric fixture incorporating one embodiment of my invention.

Fig. 2 is a plan view of a sheet metal blank or strip having suitable characteristics and from which the heat-conducting device may be formed.

Fig. 3 is a plan view of an arcuate blank from which a slightly different shaped heat-conducting means may be formed which will be adaptable to a wide angle adjustment for various types of reflectors and casings.

Fig. 4 illustrates the method of assembling a fixture incorporating one embodiment of my invention.

Fig. 5 is a transverse section through the reflector and heat-conducting device and taken on a line corresponding to line 5—5 of Fig. 1 and illustrates the distortion of the corrugations of the heat-conducting member to provide an enlarged contact area between the member and the reflector after the fixture is assembled.

Fig. 6 is a similar transverse view but taken on a line corresponding to line 6—6 of Fig. 1 and illustrates the distortion of the corrugations of the heat-conducting member to provide an enlarged area in contact with the casing.

Fig. 7 is a fragmentary detail view illustrating the blank shown in Fig. 2 after being corrugated.

Fig. 8 is a perspective view of a corrugated heat-conducting cylinder before being assembled in a fixture.

Fig. 9 is a fragmentary perspective detail view illustrating the distortion of the corrugations after having been once assembled.

Referring to the drawings in detail, the embodiment illustrated comprises a so-called flood-light fixture having a casing 1 in which is mounted a socket 2 for supporting an electric bulb 3. A reflector 4 is mounted within the casing 1 and around the lamp 3 and may be of any suitable cross-sectional contour to provide the desired illumination.

In the present instance, a glass reflector is illustrated. However, it should be understood that any suitable type of reflector may be used, and the reflector may be mounted in the casing in any suitable manner. In the embodiment illustrated, a padded ring 5 is secured around the front rim of the reflector and the ring and reflector are sup-

ported in the casing by means of suitably spaced clamps 6.

A glass cover 7 is provided for the casing and may be retained in position by means of clamps 8.

These details of construction may be of the ordinary type as they form no part of the present invention. In the present instance, the fixture is supported on an adjustable arm 9 and a band or strap 10 is clamped around the fixture and to the arm 9 by means of a thumb nut 11.

A corrugated ring-like member 12 which is preferably of very thin aluminum, or other suitable material having heat-conducting characteristics similar to aluminum, is supported by friction between the casing 1 and the reflector 4. The outer peaks of the corrugations are distorted at 12a during the assembly to provide an enlarged area in contact with the casing 13. The inner peaks of the corrugations are also distorted at 14 to provide a relatively large area engaging the reflector 4. This ring or heat-conducting band 12 is formed by corrugating the blank shown in Fig. 2 in the manner illustrated in Fig. 7. The ends of the corrugated blank are then overlapped and secured by means of a rivet 15 to form a ring or corrugated cylinder as illustrated in Fig. 8.

As previously stated, the corrugated cylinder 12 is preferably of very thin, soft material and due to the corrugations may be readily expanded or contracted to conform generally to the angular contour of a reflector when it is forced thereon.

In assembling the device, the cylinder 12 is placed around the reflector 4, as illustrated in Fig. 4, where it assumes a conical relation conforming to the shape of the reflector. The reflector and cylinder thereon is then inserted in the casing 1 until the corrugated member is engaged thereby. The reflector is then forced inwardly distorting the peaks of the corrugations to provide sufficient contact area as described previously, and the reflector is then secured in place by means of the suitably spaced clamps 6. By this method the outer peaks of the corrugations are forced into close contact with the casing over a comparatively large area, as illustrated in Fig. 6, and the inner peaks of the corrugations are also forced into close contact with the outer surface of the reflector 4 over a comparatively large area as shown in Fig. 5.

The compression of the corrugations during assembly retains the member 12 snugly in position between the reflector and the casing and also provides an efficient cushioning means therebetween which is desirable with all types of reflectors and is of special importance when glass reflectors are used.

It is unnecessary to provide any supporting or fastening means for the conducting member 12 and while the blank from which the member is formed is of comparatively thin material, the corrugations provide a great number of substantially radially positioned, spaced partitions extending from the reflector to the casing whereby the heat is rapidly conducted outwardly to the casing and dissipated therefrom.

By the use of this invention, it is possible to maintain the temperature of both the lamp and the reflector at a safe point where without this means the temperature would be too great for practical use.

The material from which the member 12 is formed is very thin and its position in the fixture and axial alignment therewith provides a relatively very large heat-conducting area so disposed as to avoid interrupting air circulation within

the fixture. In fact, the longitudinal channels formed between the reflector and casing assist and the heat conductivity of the surfaces materially assists in maintaining a uniform air flow and eliminating cross swirls.

While the cylindrical embodiment previously described is adaptable to a reasonably wide angular or conical range, it is sometimes desirable to insert the heat-conducting means between a reflector and casing in which the angular relation is beyond the limits of the cylindrical construction, or in which it is desirable to position the heat-conducting device in a different position relative to the casing and reflector. In such cases, a curved blank 16 such as illustrated in Fig. 3 may be used and the corrugations or other engaging portions may be so formed and distributed that the resilient ring or band will be conical instead of cylindrical. A band of this type is also capable of compression and expansion, or relative positioning to adjust itself to a variety of angular relations, and the engaging portions of the corrugations will be deformed or depressed during the assembly in a manner somewhat similar to that previously described to provide suitable contacting areas. This type of heat conducting device is also adaptable for use with a variety of fixtures, particularly explosion-proof fixtures, such as illustrated and described in a copending Benjamin application Serial No. 653,414 filed January 25, 1933.

Modifications may be made in the embodiment illustrated and described and I, therefore, desire to be limited only by the prior art and the scope of the appended claims.

Having thus described my invention, what I claim and desire to secure by Letters Patent is:

1. A heat dissipating fixture of the character described comprising a casing, a reflector in said casing, and a corrugated soft sheet metal member snugly retained between said reflector and said casing, the tops of the corrugation being distorted to provide increased contact surfaces in heat conducting relation with said reflector and said casing.

2. A heat dissipating fixture of the character described comprising a casing, a reflector in said casing, and a longitudinally corrugated cylinder of thin heat conducting material between said casing and said reflector and in axial relation therewith, the tops of the corrugations being distorted to provide increased heat transferring surfaces.

3. In an electric fixture including a casing having a reflector therein, a heat conducting means between said reflector and said casing, said heat conducting means comprising a plurality of closely spaced and substantially radially disposed portions of relatively thin, soft material having high heat conducting characteristics, and deformed portions forming relatively large areas contacting with said casing and said reflector.

4. In an electric fixture having a casing and a reflector therein, means for rapidly conducting heat from the reflector to the casing comprising a sinuous sheet metal member between said reflector and said casing and having alternate portions pressed snugly against and conforming to the contacted portions of said reflector and casing respectively, said member being formed of relatively thin material having heat conducting characteristics of the order of sheet aluminum.

5. In an electrical lighting fixture a heated member, a casing therefor, and an expandable and contractible corrugated cylinder of thin,

soft, heat conducting material compressed there-between to conform generally to the contour of the heated member, and to conduct heat from said heated member to said casing.

- 5 6. An electric fixture comprising a heated member, a casing therefor, a heat dissipating means between said heated member and said casing and having portions in contact with said heated member and other portions in contact 10 with said casing, said dissipating means comprising a relatively thin sheet metal member having heat conducting characteristics substantially on the order of sheet aluminum and so

formed as to be radially compressible to cause said portions to increase the area of contact relative to increased compression between the heated element and the casing.

7. In an electric fixture having a casing and 5 a reflector therein, a substantially continuous sheet metal heat conductor around said reflector and in intimate heat conducting contact therewith and with said casing, said sheet metal being formed to provide a plurality of closely adjacent 10 passages for convection currents.

VIVIAN LUTHER WESTBERG.
